DESIGN FOR A SKILLET

Karl Schneider, Chicago, Ill., assignor to Sears, Roebuck and Co., Chicago, Ill., a corporation of New York

Application November 5, 1942, Serial No. 108,703

Term of patent 3½ years

To all whom it may concern:

Be it known that I, Karl Schneider, a citizen of Germany, resident of the United States of America, having applied for first citizenship papers of the United States, residing at Chicago, in the county of Cook and State of Illinois, have invented a new, original, and ornamental Design for a Skillet, of which the following is a specification, reference being had to the accompanying drawing, forming a part thereof.

Figure 1 is a top plan view of a skillet embodying my new design.

Figure 2 is a side elevational view of the same.

Figure 3 is a vertical sectional view taken transversely through the handle as indicated at line 3—3 on Figure 1, and on a larger scale than said figure.

The characterizing features of my design reside in the glass skillet disclosed having a handle integrally and unitarily united thereto, said handle being of the form and having surface decoration specifically as shown.

I claim:

The ornamental design for a skillet, substantially as shown and described.

KARL SCHNEIDER.
